Primary Examiner — Ian Simmons*Assistant Examiner* — Loryn K. Leblanc(74) *Attorney, Agent, or Firm* — JEEN IP LAW, LLC(57) **CLAIM**

The ornamental design for a projector, as shown and described.

DESCRIPTION

FIG. 1 is a front, right and top perspective view of a projector, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion “9” in FIG. 1;

FIG. 10 is an enlarged view of portion “10” in FIG. 5; and,

FIG. 11 is an enlarged view of portion “11” in FIG. 7.

The broken lines shown in the drawings illustrate portions of the projector that form no part of the claimed design.

The dot-dash broken lines depict the boundaries of the enlargements that form no part of the claimed design.

1 Claim, 11 Drawing Sheets(56)
